DESIGN FOR A BREASTPIN

Reuben Gershel, Philadelphia, Pa.

Application July 17, 1937, Serial No. 70,501

Term of patent 7 years

To all whom it may concern:

Be it known that I, Reuben Gershel, a citizen of the United States of America, residing at Philadelphia, in the county of Philadelphia and State of Pennsylvania, have invented a new, original, and ornamental Design for a Breastpin, of which the following is a specification, reference being had to the accompanying drawing, forming part thereof.

Fig. 1 represents a front elevation of a breastpin, showing my new design.

Fig. 2 represents a plan view of Fig. 1.
Fig. 3 represents a right hand elevation of Fig. 1.

The dominant feature of my design consists in the arrangement of a bird perched on a twig, said bird and twig being supported by a frame.

I claim:

The ornamental design for a breastpin, as shown and described.

REUBEN GERSHEL.
